(57) **CLAIM**

The ornamental design for a controller keypad, as shown and described.

DESCRIPTION

FIG. 1 is a perspective view of one preferred embodiment of a controller keypad in accordance with the invention;

FIG. 2 is a front elevation of the controller keypad shown in FIG. 1;

FIG. 3 is a left side elevation of the controller keypad shown in FIG. 1;

FIG. 4 is a right side elevation of the controller keypad shown in FIG. 1;

FIG. 5 is a top plan view of the controller keypad shown in FIG. 1; and,

FIG. 6 is a bottom plan view of the controller keypad shown in FIG. 1.

The side of the invention opposite the side shown in FIG. 2 is unadorned.
